UNITED STATES PATENT OFFICE

2,500,706

WINDOW SHADE BRACKET

Frank Oliver Roshko, New Orleans, La.

Application July 30, 1948, Serial No. 41,502

3 Claims. (Cl. 248—267)

1

This invention is an improvement in shade roller brackets of the type wherein the shade roller may be reversed in the bracket; and the primary object of the invention is to provide a bracket capable of receiving either the spade or spring end, or the pin end, of a shade roller, the holes in the pair of brackets for receiving the spade or pin being so shaped as to maintain the roller level, or horizontally disposed, regardless of which end of the shade roller is placed therein, whereby the shade roller may be reversed in said brackets and, in either position, will be always disposed horizontally.

Another object of my invention is to provide a roller bracket of slot type, pin type, or tension type, having a specially shaped spade or pin receiving hole, as set forth above, and embodying convenient means for removing the roller for reversal thereof.

Other objects and advantages of my invention will become apparent during the following discussion of the drawings, wherein:

Figure 1 is a front elevational view of a conventional shade roller, mounted between a pair of my novel brackets of the pin type.

Fig. 2 is an end view of the assembly shown in Fig. 1, showing the spade or spring end of the shade roller supported in a bracket of the pin type.

Fig. 3 is an opposite end view of the assembly shown in Fig. 1 showing the pin end of the shade roller supported in the pin type bracket.

Fig. 4 is an end view of a modified form of the bracket, of the slot type.

Fig. 5 shows another modified form of bracket illustrating the tension or spring type.

Fig. 6 is a top view of the bracket shown in Fig. 5, taken along line 6—6 of Fig. 5.

Referring to Figs. 1, 2 and 3 of the drawings, the bracket 1 is of the pin-type, same having a flange 1a at its inner end, with holes 1b therethrough adapted to receive mounting screws 2. The outer end 1c of the bracket 1 is of substantially semi-circular shape and a shade roller pin receiving hole 1d is located at the axis of curvature of said semi-circular end 1c. The shade roller 3 has a pin 3a at one end, and a spade 3b at the other or spring end, the spade 3b being of the conventional spring operated type. Extending diametrically across the pin receiving hole 1d is a vertically disposed spade receiving slot 1e, the respective centers of hole 1d and slot 1e being coincident.

In the embodiment shown in Figs. 1, 2 and 3, a forwardly and upwardly extending inclined opening 1f in bracket 1 is provided, the width of the

2

opening 1f being sufficient to pass the pin 3a for removal or insertion of the roller pin 3a in the bracket. The lower wall of opening 1f is tangent to the lower periphery of hole 1d while the upper wall is substantially parallel with the lower wall and converges at the upper portion of slot 1e providing a downwardly extending lip 1x adjacent the upper end of slot 1e at the outer wall thereof. In this modification, the spade end 3d of the shade roller 3 would be first inserted directly into the slot 1e in one bracket 1, and then the pin end 3a of said shade roller 3 could be passed directly through the slot 1f in the other bracket 1 so that the pin would seat in the related hole 1d. Since the hole 1d in both brackets is centered coaxially with the center of slot 1e, it is obvious that the spade end 3b could be entered into either of the brackets of said pair, and when the pin end 3d was seated in the other bracket the shade roller would be horizontally disposed.

Fig. 4 shows a similar bracket but with a modified slot type inclined opening 1g extending upwardly therein, said slot being wide enough to pass only the spade 3b and not the pin 3d. This form of the bracket has the advantage of holding the roller in tighter engagement with the pair of brackets, but has the disadvantage of making removal of the roller from the brackets more tedious. In this modification the lower wall of slot 1g terminates adjacent the upper end of the hole 1d rather than being tangent to the lower periphery thereof, while the upper wall of slot 1g terminates at the upper end of slot 1e, so that a shoulder 1h is left at the top of the slot 1e to prevent the roller 3 from jumping out of the bracket 1 if the shade end 3b is allowed to suddenly rewind unrestrainedly.

The tension type modification shown in Figs. 5 and 6 has no slot, such as 1f or 1g, communicating with the hole 1d and slot 1e, but the bracket is made of resilient material so that it may be flexed as shown by dotted lines in Fig. 6, from the pin 3a or spade 3b in the end of the shade roller 3 to permit removal or reversal thereof. The coaxial hole 1d and slot 1e insures that the shade roller 3 will remain horizontal when supported in brackets 1, regardless of which way the roller is supported in the brackets, since in reversible positions the center of the roller 3 is supported at the same height by the spade receiving slot 1e or pin receiving hole 1d. It is important that the roller be mounted horizontally to insure even winding of the shade thereon, and to cause the shade to hang straight, particularly

where it is long and narrow, as when used at French-type doors.

I do not limit my invention to the exact forms shown in the drawing, for obviously changes may be made therein within the scope of the claims.

I claim:

1. Brackets for reversibly supporting a conventional shade roller having mounting members including a pin at one end and a spring operated spade at the other end, each bracket comprising a plate; means for mounting said plate at its inner end to a support; said plate having a circular hole adjacent the outer end thereof for receiving said pin and having an elongated vertically disposed slot therein for receiving said spade; the center of the slot being coaxial with the center of said hole.

2. Brackets for reversibly supporting a conventional shade roller having mounting members including a pin at one end and a spring operated spade at the other end, each bracket comprising a plate; means for mounting said plate at its inner end to a support; said plate having a circular hole adjacent the outer end thereof for receiving said pin, and having an elongated vertically disposed slot therein for receiving said spade, the center of the slot being coaxial with the center of said hole; an inclined slot in said plate for the passage of said mounting members into said vertical slot and hole, said inclined slot sloping upwardly from the outer corner of the top of said vertical slot, above said hole and providing a shoulder at the upper end of the vertical slot for preventing said mounting members from jumping out of said vertical slot, said inclined slot being of slightly larger width than said spade.

3. Brackets for reversibly supporting a conventional shade roller having mounting members including a pin at one end and a spring operated spade at the other end, each bracket comprising a plate; means for mounting said plate at its inner end to a support; said plate having a circular hole adjacent the outer end thereof for receiving said pin, and having an elongated vertically disposed slot therein, for receiving said spade, the center of the slot being coaxial with the center of said hole; an inclined slot in said plate for the passage of said mounting members into said vertical slot and hole, said inclined slot sloping upwardly from the outer side of the vertical slot, with its lower wall substantially tangent to the lower periphery of said hole, and its upper wall forming a lip adjacent the outer corner of the vertical slot to prevent said spade from jumping out of said vertical slot, said inclined slot being of slightly larger width than said pin.
